CLAIM

The ornamental design for an module for optical wiring, connector for optical wiring, and connector for optical wiring with module for optical wiring, as shown and described.

DESCRIPTION

FIG. 1 is a front perspective view of a module for optical wiring showing our new design;

FIG. 2 is a rear perspective view thereof;

FIG. 3 is a front elevational view thereof;

FIG. 4 is a rear elevational view thereof;

FIG. 5 is a top plan view thereof, the bottom plan view being a mirror image thereof;

FIG. 6 is a right side elevational view thereof, the left side elevational view being a mirror image thereof; and,

FIG. 7 is an enlarged cross sectional view taken along a line 7—7 shown in FIG. 3 thereof.
